DOOR LOCK

Fred C. Schoch, Oak Park, Ill.

Application January 8, 1944, Serial No. 517,482

5 Claims.

(Cl. 70—208)

This invention relates to improvements in door locking means and particularly to a self contained baseless door lock unit embodying a handle movable into a guard to render it inaccessible when in locked position.

My invention provides a compact structure adapted to be quickly, conveniently and economically mounted on the door of a cabinet, locker, truck door and the like, and in either new or replacement installations.

Other objects and advantages of my invention, including the details of construction and arrangement of parts, will be apparent from a consideration of the following specification and drawings, wherein

Fig. 1 is a front view of my novel lock unit which is adapted to be mounted on a door of the class described.

Fig. 2 is a plan sectional view of my unit taken on the line 2—2 of Fig. 1.

Fig. 3 is a fragmentary detail with parts in section illustrating the operation of the latch bolt of my unit.

Fig. 4 is a plan view detail of the handle of my unit and its stem parts.

Fig. 5 is a view of my unit partially in transverse section on the line 5—5 of Fig. 2.

Fig. 6 is a rear view of my unit with parts in section on the line 6—6 of Fig. 2.

Fig. 7 is a diagrammatic elevation of my novel lock unit in operative association with a cabinet door.

Referring to the drawings, my unit comprises an escutcheon plate or guard portion 10 adapted to be mounted on the outer face of a door 11, such as that of a metallic cabinet 12 shown in Fig. 7, by means of screws (not shown) extending through the door 11 from the inner face thereof into a plurality of threaded sockets 13 in the guard portion 10. The guard 10 is provided with a longitudinal groove or seat 14 of a depth and contour adapted to seat the handle 15 when depressed into locked position, as will be hereinafter more fully described.

Extending rearwardly of the guard 10, and preferably formed integrally therewith adjacent one end, is a tubular holder collar or spring carrier composed of the endwise spaced sections 16 and 16' reinforced and joined in alignment by means of the rib 17. The tubular collar 16 opens to the seat 14 and receives the tubular handle stem 18, the outer end of the stem being secured within the thickness of the handle and beneath the outer face thereof, as at 19. A holder rod 20 is positioned within the handle stem 18, the rod 20 being substantially the length of the joint length of the collar portions 16—16'. The handle stem 16 is longitudinally contractible of the rod 20, and expandable to the limit of the web 21 within the handle stem when brought into abutment with the head 22 of the rod 20 under the action of the

coil spring 23 interposed between the head 24 of the collar portion 16' and the handle stem or its web 21. The holder rod 20 is in turn held against withdrawal from the tubular collar portions 16—16' by means of a headed screw 25 threaded into its end 26. A second coil spring 27 may be interposed between the web 21 and the head 22 of rod 20 to retain rod 20 normally telescoped within the collar portions if the end of the rod 20 is not otherwise fixedly secured to the head 24, although spring 27 is of lighter weight or under lower normal compression than spring 23 so as not to interfere with the normal function of the latter.

15 A trigger latch 28 is mounted against the rear face of guard plate 10 in longitudinal slidable relationship by means of the headed pins 29—29 extending through the slot 30. One end of the latch is provided with the offset projection 31 which extends through the slot 32 in the wall of the collar portion 16, and is adapted to project into the groove 33 formed in the periphery of the handle stem 18. The relationship of the stem groove 33 to the latch tongue 31 is such that when 25 the handle 15 is fully seated within its seat 14 in the guard 10 the tongue 31 is projected into the groove 33, under the action of the pusher spring 34, the spring 34 being positioned between the latch ear 35 and a surface 36 within a suitable 30 groove in the guard 10. In this manner the door handle 15 is held locked in inaccessible position until the latch tongue 31 is withdrawn from the stem groove 33, after which the handle 15 is projected outwardly, as indicated by the dotted position 35 thereof in Fig. 2, under the action of its spring 23.

For release of the trigger latch, lock means are provided, preferably as illustrated, and which comprises a tumbler lock 37 received within the 40 tubular portion 38 of the guard plate 10, the lock having a cam projection 39 rotatable by means of the key 40. The cam 39 is embraced by and is adapted to act against the inward projection 41 from the latch offset portion 42. The full 45 illustration of Fig. 2 shows the cam 39 turned to the locked position, or rather the position in which the trigger latch is permitted to be projected for handle locking engagement under expansion of spring 34. The dotted position of 50 latch 28 in Fig. 2 shows the position to which the latch is moved by manipulation of key 40 which causes cam 39 to bear against the latch projection 41 and to thereby slide the latch and its locking tongue 31 out of engagement with 55 groove 33. To permit the handle 15 to be locked in depressed position the key 40 is rotated to locking position or to the position which permits the latch to slide under the action of its spring 34, in the direction towards the stem 60 handle 18.

My novel unit further comprises a latch swing

bolt 43 carried on the handle stem 18, the latch bolt being rotatable with the handle stem by actuation of the handle 15, when the latter is released and outwardly projected. As illustrated in the detailed view of Fig. 3, the latch bolt 43 is of the tongue type adapted to be brought into and out of locking engagement by pivotal movement to and from horizontal position, and to be thereby brought into and out of engagement with suitable keeper means such as the illustrated cabinet vertical face flange 44, or like fixed or fixable surface adjacent the side of the door on which the unit is mounted, or arcuate groove or the like shaped keeper (not shown).

The latch bolt 43 is engaged for rotatable movement with the handle 15 or its stem 18 by means of a key and keyway engagement which, however, permits the handle stem 18 and the bolt 43 to slide relative to each other. Thus, as illustrated, the stem 18 is provided with a planar surface portion extending longitudinally thereof as at 45 and the tongue bolt is provided with a similarly shaped recess through which the stem 18 extends. The two parts are locked against relative rotation preferably in a position where the tongue of the bolt 43 extends parallel to the handle 15 and in the opposed direction. The bolt 43 is further retained against movement longitudinally of the stem 18 by being positioned between the spaced adjacent ends of the collar portions 16-16', but is permitted to be pivotally rotated therebetween to the limits of the rib 17. When the stem embracing portion of the latch bolt is provided with an enlarged circular flange 46 for the purpose of permitting actuation of supplemental bolt means, the enlarged flange is provided with an arcuate slot 47 of sufficient extent to permit necessary free pivotal movement of the bolt 43 but to otherwise limit pivotal movement by means of abutment of the terminal ends of slot 47 against rib 17.

As indicated by the details of Fig. 3 and the illustration of Fig. 7, my unit is adapted to actuate supplemental bolts such as the pair of vertically reciprocable bolts 48 which may seat against suitable keeper means, such as against the inner surface of the upper and lower cabinet defining flanges 49, or within suitable slots or other keeper members positioned thereat. The bolts 48 are each connected to a throw rod 50, the opposed end of each rod being pivotally engaged to the rotatable flange portion 46 adjacent the periphery thereof as at 51. The throw rods 50 are engaged to the flange 46 adjacent to but laterally offset from its vertical center when the tongue of the latch bolt 43 is in horizontal position. When the handle 15 is extended and freely rotatable, manipulation thereof permits vertical reciprocation of the supplemental bolts 48 simultaneously with the pivotal movement of the latch bolt 43, as illustrated by the dotted position.

In a construction such as the elongated cabinet door illustrated in Fig. 7, or other door installations where added or plural bolt means are desired I preferably employ both the vertically reciprocable and pivotal bolt means as illustrated, although it will be understood that I may, if desired, employ either alone. It will also be apparent that my device may be conveniently and quickly installed on new or existing equipment and is self-contained as a unit.

I claim as my invention:

1. A door lock unit comprising a mounting

plate, an integral guard projecting from the face thereof, an integral tubular holder opening within said guard and projecting rearwardly of said plate, a handle movable into and out of said guard having a stem telescopically engaged in said holder and contractible therein, a swing bolt held against axial movement by said tubular holder and carried by said handle stem and engaged thereto for pivotal movement thereby, trigger latch means secured on the back of said plate for maintaining said stem in retracted position within said holder with the handle in seated position within the guard, and key means operable from the face of said plate for retracting said trigger latch means and for permitting the handle to be operatively extended from said guard.

2. A door lock unit comprising a mounting plate, a guard on the face of said plate, a tubular holder opening within said guard and projecting rearwardly of said plate, a handle having a stem telescopically and slidably engaged in said holder, a swing bolt engaged to said handle stem for pivotal movement therewith and projecting through a lateral slot formed in said holder, and trigger latch means engageable with said handle stem for maintaining said handle in inaccessible position within said guard.

3. A door lock unit comprising a mounting plate, a guard opening forwardly thereof, a tubular holder opening within said guard and projecting rearwardly thereof, a handle having a stem telescopically and slidably engaged in said holder, spring means in said holder for projecting said handle to operative position, a swing bolt engaged to said handle stem for pivotal movement therewith and projecting through a transverse slot formed in said holder, said bolt being maintained by said holder against movement longitudinally thereof and said stem being longitudinally reciprocable with respect to said holder and bolt, and trigger latch means releasable from the face of said plate for maintaining said stem in retracted position with said handle seated within the guard.

4. A door lock unit comprising a mounting plate, a guard opening forwardly thereof, a tubular holder opening within said guard and projecting rearwardly thereof, a handle having a stem telescopically and slidably engaged in said holder, spring means in said holder for projecting said handle to operative position, a swing bolt engaged to said handle stem for pivotal movement therewith and projecting through a transverse slot formed in said holder, said bolt being maintained by said holder against movement longitudinally thereof and said stem being longitudinally reciprocable with respect to said holder and bolt, and trigger latch means releasable from the face of said plate for maintaining said stem in retracted position with said handle seated within the guard comprising a trigger latch secured rearwardly of said plate and endwise reciprocal through a lateral opening formed in said holder and engageable therethrough with engagement means formed on the handle stem.

5. A door lock unit comprising a mounting plate, a guard on the face of said plate, a tubular holder opening within said guard and projecting rearwardly of said plate, a handle having a stem telescopically engaged in said holder, a swing bolt carried by said handle stem and held against axial movement by said tubular holder, and trigger latch means secured on the back of said plate for maintaining said handle in seated position within said guard.

FRED C. SCHOCH.
